UNITED STATES PATENT OFFICE.

ROBERT M. PIERSON, OF AKRON, OHIO, ASSIGNOR TO THE B. F. GOODRICH COMPANY,
OF NEW YORK, N. Y., A CORPORATION OF NEW YORK.

DUST-CAP.

1,287,423.

Specification of Letters Patent. Patented Dec. 10, 1918.

Application filed August 6, 1918. Serial No. 248,626.

To all whom it may concern:

Be it known that I, ROBERT M. PIERSON, a citizen of the United States, residing at Akron, in the county of Summit and State 5 of Ohio, have invented a certain new and useful Dust-Cap, of which the following is a specification.

This invention relates to covers or caps for inclosing a pipe-end such as the casing 10 of an inflating-valve for pneumatic tires in order to protect the same and exclude water from entering through the valve-hole in the felly into the space between the rim and the tire. My object is to provide an improved 15 article of this class which may be applied and removed without the laborious operation of screwing it over a long thread. My improved cap is particularly adapted to be coupled to the familiar externally-threaded 20 type of inflation-valve casing which is provided with longitudinal flats on opposite sides, but it may be used in any situation to which it is found applicable.

Of the accompanying drawings,

25 Figure 1 is a side elevation, partly in section, showing a preferred form of my improved cap applied to a pneumatic tire valve.

30 Fig. 2 is a section on the line 2—2 of Fig. 1.

Fig. 3 is a side elevation, partly in section, showing a modification.

35 Fig. 4 is a section on the line 4—4 of Fig. 3.

Referring at first to Figs. 1 and 2, 10 is a part of the wheel felly having a radial aperture 11 through which passes an inflation-valve casing 12 of the usual type formed with a screw thread 13 which is interrupted 40 by flat portions 14 on two sides to prevent the rotation of said casing in the spreader lug at the tube (not shown). 15 is the usual nut engaging the thread 13 and abutting against the inner periphery of the felly for drawing said lug against the tire rim.

45 16 is my improved dust cap or protector which is made of soft vulcanized rubber (under which term I include semi-soft rubber), and is formed as a tube closed at the outer 50 end and of general cylindrical form, but provided at and near the mouth of the cap with two flat portions 17 on opposite sides interposed between two arcuate portions.

55 These flat portions correspond to the two flat surfaces 14 and may have any suitable

location along the sides of the cap where they can engage the thread 13, although I prefer to locate them at the mouth of the cap. They might extend farther along the cap than shown, but are preferably made 60 relatively short so as to avoid an undue amount of friction when the cap is turned into its locking position. The mouth end of the cap acts as a gripper, and the size of its aperture is such that there is a very slight 65 clearance (or none at all) between said cap and the valve casing when the cap is in its unlocked position, as represented in the drawings.

In operation, when the cap is positioned 70 so that its flat portions 17 register with the flat surfaces 14 on the valve casing, as indicated in Figs. 1 and 2, it may be freely moved longitudinally over said casing. To apply and locate the cap in its most advanced position so as to protect both the 75 valve casing and the aperture 11 against the entrance of dirt and water, said cap is pushed into place until its inner end abuts against the nut 15, and is then given substantially a quarter-turn clock-wise from the 80 position shown in Figs. 1 and 2 in order to cause both portions of the screw thread 13 on the valve casing to bite into the flat portions 17 of the cap. This tends slightly to 85 distort the mouth end of the cap, spreading the flat portions 17 farther apart and drawing together the intervening arcuate portions so that the cap grips the valve casing, the 90 resiliency of the rubber, combined with its frictional holding qualities, serving to hold the cap from accidentally unscrewing. While the flat portions 17 might be internally molded with portions of a screw thread 95 complementary to the thread 13, it is preferred merely to rely upon the indenting and stretching of the rubber by the metallic threaded portions of the valve casing.

In the modification shown in Figs. 3 and 4, I make the body part of the cap in the 100 form of a metal cylinder 18 closed at one end and formed near its mouth with two opposite holes 19. The locking member is a sleeve 20 of vulcanized soft or semi-soft rubber inclosed within the mouth end of the 105 metal cylinder and corresponding in function to the inner or mouth portion of the all-rubber cap 16 shown in Figs. 1 and 2, said sleeve having flat portions 17a corresponding to the flat portions 17, and being fur- 110

ther formed, preferably on said portions 17*, with a pair of integral, radial studs 21 which occupy the apertures 19 in the metal member to interlock said member and sleeve 5 as to relative rotary motion. The studs may serve as convenient finger-holds for turning the cap on the valve casing. I further prefer to form the inner end of the sleeve 20 with an integral flange 22 to act as an end 10 bearing or gasket under the edge of the metal body 18 when the cap is forced against the nut 15. In this form of the invention, the rigid tubular member 18 limits the amount of expansion of the sleeve 20 and 15 hence tends to prevent any substantial permanent enlargement of the latter, such as may occur when the sleeve is made with a relatively-thin wall.

Various other changes may be made within 20 out departing from the scope of my invention.

I claim:

1. The combination with a pipe-end 25 formed externally with a mutilated screw thread, of a cap adapted to inclose said pipe-end and provided with an annular locking portion of relatively soft stretchable material, said cap being adapted in one 30 rotary position thereof to move freely in a longitudinal direction over the pipe-end, and to interlock with the thread thereof by a turning movement of the cap.

2. The combination with a pipe-end having an external screw thread interrupted by 35 longitudinally-extending plain portions, of a cap inclosing said pipe-end and having a soft-rubber gripper adapted to engage and disengage said thread by a rotary movement of the cap.

40 3. A cap for inflating valves having an annular gripper composed of soft rubber and formed with a pair of opposite arcuate portions and a pair of intervening, opposite substantially flat portions.

45 4. The combination with a pipe-end having an external screw thread, interrupted

by opposite longitudinally-extending flat surfaces, of a cap inclosing said pipe-end and having an annular soft-rubber gripper formed with opposite arcuate portions 50 and intervening opposite flat portions freely movable longitudinally over the pipe-end when registered with the corresponding portions on the latter, the said flat portions being adapted to interlock with the thread 55 on the pipe-end by a rotary movement of the cap.

5. A cap for inflating valves composed throughout of vulcanized soft rubber of tubular form, closed at one end and provided 60 internally with opposite flat portions in its side walls adjacent to the mouth of said cap.

6. The combination with a pipe-end having an external screw-thread interrupted by 65 opposite longitudinally-extending flat surfaces, of a flexible rubber cap therefor having a tubular body adapted to surround but not grip said screw-thread, and a reduced mouth portion adapted to surround and 70 grip the thread.

7. The combination of a wheel felly having a radial aperture, an inflating-valve casing projecting through said aperture and formed with an external screw thread interrupted by longitudinally-extending flat portions, a nut on the casing abutting against the inner periphery of the felly, and a cap having at its mouth end an annular soft-rubber gripping and packing portion 80 closely embracing the valve casing and abutting against the nut, said gripping and packing portion having an opening corresponding to the cross-sectional shape of the valve-casing, the flat portions of the walls 85 of said opening being adapted to grip the screw-thread on the valve casing when the cap is turned thereon.

In testimony whereof I have hereunto set my hand this 5th day of August, 1918.

ROBERT M. PIERSON.
